UNITED STATES PATENT OFFICE.

LLEWELLYN W. JONES, OF SEWICKLEY, PENNSYLVANIA.

FILTER.

No. 818,698.

Specification of Letters Patent.

Patented April 24, 1906.

Application filed April 13, 1905. Serial No. 255,375.

To all whom it may concern:

Be it known that I, LLEWELLYN W. JONES, a resident of Sewickley, in the county of Allegheny and State of Pennsylvania, have invented a new and useful Improvement in Filters; and I do hereby declare the following to be a full, clear, and exact description thereof.

My invention relates to filters, and more especially to a device for stirring up the sand and water during the process of cleansing the filter.

The chief object of my invention is to provide a stirring device which will withdraw itself automatically from the body of sand when the same is allowed to settle after the stirring process, and so avoid the necessity of leaving the stirring device embedded in the sand during the filtering process.

To these ends my invention comprises, generally stated, in connection with a sand filtration-bed, a stirring device and means for withdrawing said stirring device automatically from the sand as the sand gradually settles after the washing operation.

To enable others skilled in the art to make and use my invention, I will describe the same more fully, referring to the accompanying drawings, in which—

Figure 1 is a plan view of a suitable filter. Fig. 2 is a vertical section of same. Fig. 3 is a section on the line 3 3, Fig. 1; and Fig. 4 is a detail view.

Like numerals indicate like parts in each of the figures.

In the drawings the numeral 2 designates a suitable tank or receptacle adapted to contain the filter-bed. The bottom of said tank has the pipes 3 arranged therein, said pipes having the nozzles 4 and said pipes connecting with the central channel 5, within which the water is collected and carried off to the supply-pipes. The construction of the filter-bed may, however, be of any suitable construction, and I make no claim to this particular feature of the filter-bed.

Within the tank 2 is the sand bed 6, down through which the water passes to the nozzles 4. Secured to the inner walls of the tank 2, at a suitable height, is the trough 7, to which the water is supplied by the inlet-pipe 8. This trough is annular in form and is supported by the brackets 9. The water entering this overflows therefrom in an even stream onto the filter-bed 6.

A vertical shaft 10 is mounted in bearings

in the casting 11, which forms the channel 5, said shaft being protected by the tube 12. This shaft 10 passes up through suitable bearings in the beams 13, which extend across the top of the tank 2. To the upper end of the shaft 10 is secured the gear-wheel 14, which meshes with the pinion 15 on the counter-shaft 16, mounted in the bracket 17 on the beams 13. This counter-shaft 16 has the bevel-gear 18, which meshes with the bevel-pinion 19 on the horizontal shaft 20. This shaft 20 has the pulley 21, which may be connected up by a belt to a motor or other engine and by means of which power is transmitted to rotate the vertical shaft 10.

Secured to the shaft 10 is the rotary beam 22, said beam being made up of suitable angle-bars 23. Secured to the bottom of the rotary beam 22 are the angle-bars 24, to which are attached the flexible nets 25. These nets are made up of links of any suitable form. Any suitable form of mesh may be employed, that shown consisting of the round links connected by oblong links. This may be varied, however, to suit different conditions.

The bars 24 project in under the trough 7, whereby the nets are adapted also to extend under said trough, and so extend substantially the entire diameter of the tank 2. By this construction, when stirring, even the sand under the trough is reached and thoroughly agitated. In order that the links of the two nets may not move in the same planes in describing the circle I arrange one of the nets closer to the vertical shaft 10 than the other one, which is arranged correspondingly closer to the walls of the tank. In this way the links of the nets may be said to break joint with each other, and so a more effective stirring of the contents of the tank is obtained.

When my improved stirring device is in use, the water from the inlet-pipe 8 is shut off from the trough 7 and the waste-pipe 26 is open. The water for washing is then admitted from below and entering the channel 5 passes up through the nozzles 4 up into the filter-bed. The force of the water acts to lift the sand and it mixes thoroughly with the water. Power is then applied to rotate the shaft 10 and through it the rotary beam 23. As the beam rotates the nets 25 are carried with it and act to thoroughly agitate and stir the sand and water, so that the particles of sand are thoroughly separated and

cleansed, the refuse or scum collecting at the top overflowing into the trough 7 and being carried off through the waste-pipe 26. This process of stirring is continued until the 5 filter-bed has been thoroughly washed, whereupon the supply is cut off from the channel 5 below and the sand allowed to settle in the bed. During the settling process the rotation of the beam 23 is continued and the net 10 25 acts to stir the settling sand, and as the sand settles in a solid mass the net gradually withdraws from the sand and rests upon the top thereof, the different lines of links assuming a horizontal position as the height of the 15 sand bed increases until the sand has entirely settled, whereupon the net will assume the horizontal position indicated in Fig. 4. By still further continuing the rotation of the beam 23 the net will act to drag along the upper 20 surface of the sand and scrape or rake the same, so as to remove any impurities collected on the top of the sand bed.

By this construction I am enabled to provide for the agitating or stirring of the sand 25 and water and provide for the gradual withdrawal of the stirring device automatically as the sand settles.

If it is found that the net does not withdraw itself sufficiently from the sand bed 30 toward its inner end or adjacent to the shaft 10, a portion of the links may be cut out, as indicated in dotted lines in Fig. 2, for it is apparent that the rotation of the net will not be so rapid toward the center as toward the 35 outer end.

By my arrangement I dispense with the rigid stirring-arms, which do not extend underneath the trough 7 and which remain in the filter-bed during the filtering process. 40 No attention need be paid to my improved stirrer after it is put in operation, for of its own self it will act to withdraw from the mass of sand and when free therefrom will remain lying upon the surface, as indicated in Fig. 4.

Although I have referred in the specification and claims to the stirring devices as "nets," I do not wish to convey the idea that I limit myself in any way to a net actually composed of links, but include within the 45 50 term any form of flexible net-like structure by means of which the body of water and sand will be stirred up and the stirrer with-

draw itself automatically as the sand is allowed to settle after washing.

What I claim is—

1. The combination of a filter-bed, a stirrer therein, comprising a net formed of links, and means for withdrawing said net.

2. The combination of a filter-bed, a net extending down into said filter-bed, and means for moving said net through said filter-bed.

3. The combination of a filter-bed, a net extending down into the filter-bed, and means for moving said net around a center.

4. The combination of a filter-bed, a net composed of links extending down into said bed, and means for moving said net around a center.

5. The combination of a filter-bed, a rotary beam, and a net depending from said beam.

6. The combination of a filter-bed, a rotary beam, and a net composed of links depending therefrom.

7. The combination of a filter-bed having a trough extending around same, a rotary net extending down into said bed and projecting under said trough.

8. The combination of a filter-bed, a vertical rotary shaft, a beam carried by said shaft, and a net carried by said beam.

9. The combination of a filter-bed, a vertical rotary shaft, a beam carried by said shaft, a net secured to said beam on opposite sides of said shaft.

10. The combination of a filter-bed, nets comprising links extending down therein, means for moving said nets around a center, one of said nets being closer to said center than the other.

11. The combination of a filter-bed, a stirrer comprising a net extending down into said bed, and means for moving said net through said bed.

12. The combination of a filter-bed, a rotary frame, and a net carried by said frame.

In testimony whereof I, the said LLEWELLYN W. JONES, have hereunto set my hand.

LLEWELLYN W. JONES.
